UNITED STATES PATENT OFFICE.

ALFRED H. RENSHAW, OF NOROTON, CONNECTICUT, ASSIGNOR TO FEDERAL SIGNAL COMPANY, OF ALBANY, NEW YORK, A CORPORATION.

MECHANISM FOR CONTROLLING RAILROAD-SIGNALS.

1,137,084.

Specification of Letters Patent. Patented Apr. 27, 1915.

Application filed October 6, 1913. Serial No. 793,514.

To all whom it may concern:

Be it known that I, ALFRED H. RENSHAW, a citizen of the United States of America, residing at Noroton, in the county of Fair-
field and State of Connecticut, have invented
certain new and useful Improvements in
Mechanism for Controlling Railroad-Sig-
nals, of which the following is a specifica-
tion.

10 My invention comprises means to operate
a railroad signal by means of an electric
motor and a train of gears and other neces-
sary accessories. In this type of signal
mechanisms the motor is required to lift the
15 signal from the stop or danger position of
indication to that of the clear or proceed
position of indication, thereby storing up
energy by virtue of the counterweight of the
semaphore signal sufficient to rotate the
20 gearing and motor in a reverse direction
when it is necessary to display the stop or
danger indication.

It is the purpose and intent of this invention
25 to so arrange the mechanism that the
factor of safety will be increased, and this
is especially accomplished by mechanical ar-
rangements whereby the brushes which con-
vey the electricity to the windings of the
30 motor are removed after the semaphore has
reached its position corresponding to the
proceed indication.

Figure 1, shows the motor and mecha-
nisms and semaphore arm in a position in-
dicating stop or danger. Fig. 2, shows the
35 motor, mechanism and semaphore in a pos-
ition indicating proceed or clear.

It will be noted that in Fig. 2 the brushes
are removed from contact with the commu-
tator of the motor armature.

40 To make the operation of this mechanism
clear, I will now describe the arrangement
in detail.

Referring to Fig. 1: The armature of the
motor, A, is attached to pinion, 1, which
45 engages spur gear, 2. To spur gear, 2, is
attached pinion, 3, which engages with spur
gear, 4. Spur gear, 4, drives spindle, 11,
to which are attached semaphore arm, 20,
and cam plate, C; cam plate, C, is provided
50 with a portion of reduced radius, 5, and of
one increased radius, 9.

It will be noticed that battery, B, is so
connected that when the switch, S, is closed,
55 current will flow through the motor arma-
ture and through the field windings, F, to

cause the motor to rotate; such rotation will
cause the semaphore arm, 20, to move from
the position shown in Fig. 1 to that of Fig.
2, this motor circuit being completed through
the contact plate, 8, carried on the retaining 60
arm, 12. This retaining arm is pivoted on
the stop, 7, and has at one extremity a roller,
6. This roller rides on the top of cam plate,
C, and when the depressed portion of the
cam plate, C, has been moved to a position 65
adjacent to roller, 6, magnet, M, which is
also energized from battery, B, will attract
arm, 12, causing roller, 6, to fall into the
depression, 5, thus retaining the semaphore
arm, 20, in the position shown in Fig. 2. 70
The interruption of the motor circuit by
means of the movement imparted to contact
plate, 8, will allow the motor to stop ro-
tating. When the arm, 20, has been moved
to the position of Fig. 2, the projection, 9, 75
of cam plate, C, will have come in contact
with the end of push rod, 10, depressing it
downward as shown in Fig. 2. This move-
ment of push rod, 10, will impart a move-
ment to each of the two brushes on the motor 80
armature moving them away from the com-
mutator of the said armature so that they
will no longer touch the said commutator.
This then will permit of the motor starting
85 to rotate in the reverse direction very easily
whenever it should be desired to release the
semaphore arm, 20, from the position to
shown in Fig. 2. If it be now desired to
cause the semaphore arm to assume the stop 90
or danger position, such movement will be
effected by opening switch, S. This will
interrupt the current flow to magnet, M,
which in turn will release the retaining arm,
12, and the counterweight of the semaphore 95
arm, 20, will drive the mechanism and train
of gears and motor armature backward, the
roller, 6, being free to slide out of the de-
pressed portion, 5, of the cam plate, C.
After such motion has begun the brushes 100
will again assume contact with the commu-
tator of the motor by means of the counter-
weights, 14, these counterweights being suffi-
cient to overcome the weight of the push
rod, 10, and the friction of the pivots upon
105 which the brushes are suspended.

What I claim as my invention and desire
to secure by Letters Patent is:

1. In a railway signal, the combination of
a signal biased to one position of indication;
a mechanism to operate the signal in oppo- 110

sition to its bias; an electric motor to operate said mechanism; a circuit controller operated by the signal to open the electric circuit to the motor; and means whereby the 5 brushes of the said motor are removed from contact with its commutator when the signal is being moved to a position of indication in opposition to its bias, said means becoming operative subsequent to the opening of 10 the electric circuit at the controller.

2. In a railway signal, a signal arm; motor brushes adapted to be moved to and from contact with the commutator of the motor; a controller to open the circuit to

the motor; and means connected with the 15 signal arm for automatically breaking and making of contact between said brushes and the commutator when the signal arm is raised to, or descends from, one of indication, said latter means operating to move 20 the said brushes subsequent to the movement of the circuit controller.

In testimony whereof I have affixed my signature in presence of two witnesses.

ALFRED H. RENSHAW.
